UNITED STATES PATENT OFFICE.

JOSHUA TURNER, OF CAMBRIDGE, ASSIGNOR TO ISAAC S. PEAR, OF BOSTON, MASSACHUSETTS.

FOLDING CAMP-CHAIR.

SPECIFICATION forming part of Letters Patent No. 231,868, dated August 31, 1880.
Application filed December 20, 1879.

To all whom it may concern:

Be it known that I, JOSHUA TURNER, of Cambridge, in the county of Middlesex and State of Massachusetts, have invented certain new and useful Improvements in Folding Camp-Chairs, of which the following is a specification.

The object of my invention is to provide a cheap, simple, convenient, and compact folding camp-chair of that class having an elastic or yielding bottom and back support, and wherein the seat-frame folds together from its sides toward the center, the back-supports folding therewith simultaneously and toward each other until they meet, so as to form a convenient handle, whereby the camp-chair may be conveniently carried; and it consists in the combination and arrangement of the pivoted back-supports to the bottom portion of the back pivoted cross-legs and their connection with the rear ends of the side pieces of the seat-frame by means of sliding screw-rings or staples connected therewith, and through which they pass or slide, so as to permit the chair to fold up, as hereinafter more fully described and set forth.

Figure 1 represents a perspective view of my invention in an open position. Fig. 2 represents a similar view of the same in a closed position. Fig. 3 represents a rear elevation of the same when open.

A A' represent the front cross-legs, pivoted together at their point of crossing by means of the rivet or bolt C, which passes horizontally through the same.

B B' represent the rear or back cross-legs, pivoted together in like manner at their point of crossing by a rivet or bolt, C. These front and rear cross-legs are connected together near their lower ends by the horizontal rounds D D', one end of which is permanently secured within holes formed in the front cross-legs, A A', their opposite ends passing through the rear cross-legs, B B', and projecting a short distance beyond, as shown, the round D' projecting through the rear cross-leg, B', farther than the round D does through the other rear cross-leg, B, both being of an equal length, and provided at their outer ends with an ex-

which fit within holes formed horizontally through the back-supports or standards F F', which are connected with the rear ends of the side pieces, E E', of the seat, which are connected rigidly with the upper ends of the front 55 and back cross-legs, A A' and B B', by means of dowels or tenons formed thereon, or in any other suitable manner, so as to form a side frame or support for the canvas or other flexible bottom, H, which is secured to said side 60 rounds or supports, E E', by being passed over the upper and outer sides thereof and fastened at each end with nails or otherwise, thus forming a central or inwardly-folding seat, as shown.

To the rear ends of the side pieces, E E', of the seat are connected staples, loops, or large screw-eyes L L', of sufficient size to permit the back-supports or standards F F' to pass through, and, when the camp-chair is folded, permit the said screw-eyes to slide upward on 70 the standards or back-supports F F', the upper portions extending some distance above the said seat or bottom H, and are provided with a canvas or other flexible back-rest or back-support, K, secured at each end to the standards F F' 75 with nails, or in any other suitable manner, so as to allow the camp-chair to fold up, as shown in Fig. 2, the said canvas back-piece K being folded around the upper ends or top portions of the said standards F F', so as to form a convenient handle to carry such camp-chair by whenever desired.

It will be seen by Fig. 3 that the back-standards F F' incline outward from their point of connection with the rounds D at their lower 85 ends to their upper ends, thus serving to increase the width of the said back-support by an increased length of the canvas K, which insures sufficient flexibility to adapt or permit the said canvas to fit the formation of the back, 90 thus forming a very easy and comfortable support or rest therefor.

Having thus described my invention, what I claim is—

1. In combination with the inwardly-folding cross-legs A A' B B', provided with the rounds D D', extending rearward through the cross-legs, the back-standards F F' pivoted thereto, and connected to the rear ends of the side pieces, E E', of the flexible seat H by the 100

sliding loops or screw-eyes L L', and provided at their upper portions with the flexible back-support K, all being constructed and arranged to fold up substantially in the manner described, as and for the purposes set forth.

5 2. In combination with front and rear cross-legs, A A' and B B', which fold from the sides inwardly, as described, the back-standards F

F', pivoted at their lower ends and joined with the side pieces, E E', of the folding seat-frame 10 by vertical sliding connections, substantially as and for the purposes set forth.

JOSHUA TURNER.
